UNITED STATES PATENT OFFICE.

MATTHEW VIERENGEL, OF BROOKLYN, NEW YORK, ASSIGNOR TO SAMUEL CUPPLES
ENVELOPE COMPANY, OF ST. LOUIS, MISSOURI, A CORPORATION OF MISSOURI.

MACHINE FOR MAKING WINDOW-ENVELOP BLANKS.

1,104,026.

Specification of Letters Patent. Patented July 21, 1914.

Application filed November 1, 1911. Serial No. 658,009.

To all whom it may concern:

Be it known that I, MATTHEW VIERENGEL, a citizen of the United States, residing in the borough of Brooklyn, county of Kings, and State of New York, have invented certain new and useful Improvements in Machines for Making Window-Envelop Blanks, of which the following is a specification.

The object of the present invention is to produce a simple and effective machine for economically producing window envelop blanks from which the window envelopes can be made in any of the usual ways.

To this end the improved machine comprises endless conveyer belts for conveying successive sheets or partially prepared blanks into and out of operative relation to the cutting devices, which cut the window opening in the sheets or blanks, the pasting devices which apply paste to sheets or blanks around the window opening, and to the patch applying devices which cut the window patch from an endless tape or web and impress it upon the pasted surface of the blank. A plurality of gage fingers is provided to intermittently move into and out of the path of the sheets or blanks to arrest them in position for the operation of the several devices referred to, one pair of sheet arresting gages being provided for each of said cutting, pasting and patch applying devices. All of the sheet arresting gages are operated in unison and have a common operating device, so that in the operation of the machine there will always be three sheets or blanks in different stages of formation.

In order that the invention may be fully understood, I will first describe the same with reference to the accompanying drawings, and afterward point out the novelty more particularly in the annexed claims.

In said drawings: Figure 1 is a side elevation of my improved window envelop blank forming machine. Fig. 2 is a plan view of the same. Fig. 3 is an end view of the same, parts being broken away for the sake of clearness. Fig. 4 is a vertical transverse sectional view illustrating the cutting or stamping device. Fig. 5 is a vertical longi-

tudinal sectional view of the same. Fig. 6 is a vertical longitudinal sectional view of the paste applying device. Fig. 7 is a similar view of the same, showing parts in shifted position. Fig. 8 is a vertical transverse sectional view of the same. Figs. 9 and 10 are detail views of parts of the patch applying device.

Any suitable frame work may be employed for properly supporting the operating parts of the improved machine. In the accompanying drawings I have shown a frame work consisting principally of the two main side frames 1 and 2 surmounted by four pairs of uprights or standards 5, 6, 7 and 8. Journaled in the standards 5 are the upper and lower feed rolls 10 and 11 into which sheets or partially prepared blanks are fed, either by hand or by an automatic paper feeding machine. Passing around these feeding in rolls 10 and 11 are the upper and lower pairs of endless feed belts or tapes 15 and 16. The carrying portions of the pairs of belts 15 and 16 extend horizontally through the machine between the uprights or standards 5, 6, 7 and 8 and are designed to engage the sheets or blanks at their lateral edges and convey them successively into and out of position for the cutting, pasting and patch applying operations of the devices presently to be explained. At the rear of the machine auxiliary brackets 9 support upper and lower feed rollers 12 and 13 between and around which the tapes 15 and 16 pass. These rollers 12 and 13 are the delivery rollers which are designed to pass the completed window envelop blanks out of the machine to a receiving table, a jogging machine, printing press, envelop machine or other machine designed to operate upon them.

The upper pair of feed tapes or belts 15 pass from the delivery rollers 12, over suitable guide pulleys 20, 21, 22 and 23 which are journaled in brackets mounted upon the standards above referred to. The lower tapes or belts 16 pass from the delivery roller 13 around guide rollers 25, 26 and 27 mounted in suitable brackets of the machine frame.

Journalized in each pair of uprights or standards 6, 7 and 8 is a transverse shaft 30, preferably square in cross-section with rounded ends which are journaled in the said standards. Adjustably mounted upon each of the shafts 30 is a pair of sheet arresting gage fingers 31 secured upon the shaft by means of the clamping devices 32. The lower ends of these gage fingers 31, beneath their supporting shaft 30, pivotally engage the ends of a cross rod or bar 35 rigidly mounted between and connecting two longitudinal bars 40. The bars 40 through the rods 35 connect the three pairs of sheet arresting gage fingers 31. Adjacent to the rear end of the machine, the bars 40 are connected by a transverse rod 41 which engages the slotted end of a rock arm 43, forming the adjustable member of a bell 20 crank lever. The arm 43 is journaled at 44 inside of the machine frame and rests between the lateral lugs 45 of an arm 46 which is also journaled at 44. Adjusting screws 47 are threaded in lugs 45 and engage the opposite edges of arm 43 to hold the same in the desired adjusted relation to the arm 46. Rigidly mounted upon the shaft 44 is an arm 48 carrying anti-friction roller 49 operating in engagement with cam 25 50, carried upon the end of a transverse shaft 51.

It will be observed that the cam 50 actuating the bell crank lever 43, 46, 48, will reciprocate the bars 40 to move the gage fingers 31 into and out of the path of the sheets or blanks carried through the machine between the tapes 15 and 16. It will be understood that the gage fingers 31 and the operating bell crank lever are made adjustable 40 to suit different sizes and shapes of blanks and window openings.

Blanks passing from the feeding in rolls 10 and 11 are conveyed by the tapes 15 and 16 to a position between the standards 6, 45 where they are arrested by the first pair of gage fingers 31. When the sheets or blanks are cut into the form of envelop blanks before feeding into the machine, I prefer to arrange the fingers 31 to engage the lateral 50 notches in the leading edge of the blank. These gage fingers 31 position the blank between the upper and lower members of the window cutting device, which will now be explained. 60 is a transverse bar adjustably 55 secured between the uprights or standards 6 by means of bolts 61 passing through the standards and engaging the slotted ends of the bar. The bar 60 is adjustable transversely of the machine and can readily be 60 removed by taking out bolt 61 for the removal of the die or the insertion of a die of different size or shape. This transverse bar 60 carries the hollow member 65 of the cutting die, the bar having a vertical opening

66 through it to allow the upward passage 65 of waste cut from the blanks. Pneumatic or other suitable means may be provided to take the waste away from the hollow die member.

Mounted beneath the hollow die member 70 65 is the cooperating male die member 70 mounted upon the vertically reciprocating cross bar 71, operating in the vertical guide ways 72 formed on the inner faces of standards 6. This bar 71 has a downwardly 75 presented frame or carrier 73 having anti-friction rollers 74, operating upon cams 75 secured to the transverse shaft 76. The lower ends of the frame 73 carry a cross bar 77 upon which is journaled an anti-friction 80 roll 78 operating upon central cam 79 also mounted upon the shaft 76. The cam 79 moves the frame 73 downwardly, and the cams 75 move the frame 73 upwardly.

When the sheet or blank arrives in position between the upper and lower cutters 65 and 70 the gage fingers 31 arrest the sheet or blank while the tapes 15 and 16 continue to move past the blank. When the blank is in position the lower movable die moves 90 upwardly to cut the window in the blank, and then returns to lowered position, after which the gage fingers 31 move out of the path of the blank and permit the tapes 15 and 16 to carry it forward to a position beneath the paste applying devices.

When the sheet or blank reaches the pasting device, the second set of gage fingers 31 arrest its position and hold it against movement while a line of paste is applied to the 100 face of the blank surrounding the window opening. The pasting device comprises a lower stationary rectangular bar 85 mounted between the uprights or standards 7 and an upper vertically reciprocating bar 86 mounted to move in the guide ways 87 of the uprights, and having pivoted to trunnions 88 at its ends the vertical pitman 89 carrying in their lower ends anti-friction rollers 90 which operate upon the cams 91 secured to 110 a transverse shaft 92 suitably journaled in the machine frame. The lower face of the pasting bar 86 is provided with a rubber pad 86^a of the proper size and shape to correspond with the size and shape of the window opening cut into the blank. Secured to the standards 7 on one side is a paste receptacle 100 in which operates a distributing roll 101. An adjustable scraper bar 102 is mounted upon the paste receptacle adjacent 120 to the roll 101.

The fountain or distributing roll 101 is mounted upon a shaft 101^a suitably journaled in the side supports of the fountain 100 and carrying at one end a sprocket wheel 101^b around which operates a sprocket chain 103 driven by a sprocket wheel 104, secured to one end of the shaft 92. 105 is a horizon-

tally reciprocating frame formed with slots 106 receiving the projecting ends of scraper bar 102 and engaging the inwardly presented pins or lugs 107 mounted upon the uprights 5 or standards 7. This frame 105 supports at its inner end a transverse shaft 110 which is journaled at its ends in the frame 105 and carries a central pasting roll 111 which is designed to be moved into contact with the 10 fountain roll 101 to take therefrom a supply of paste and move beneath the pasting pad 86^a of plunger 86 to apply a film of paste to said pad. The frame 105 is reciprocated horizontally by means of two rock arms 115 15 which are fixed to and depend from the rock shaft 116 journaled in bracket plates 117 supported upon the standards 6 and 7. This rock shaft 116 has secured to one end a rock arm 118 to which is pivoted at 119 the 20 vertical pitman 120 formed with a slotted guide yoke 121 at its lower end, which straddles the shaft 76. An anti-friction roller 122 is journaled upon the pitman 120 in position to operate upon a cam 125 secured 25 to the shaft 76.

It will be understood from the above description of the paste applying device that when the paste applying plunger 86 is raised as shown in Fig. 6, the frame 105 is 30 moved rearwardly to cause the pasting roll 111 to travel over the face of the pasting pad 86^a. As the plunger 86 prepares to descend the frame 105 moves from beneath the plunger to again move the pasting roll 35 111 into peripheral contact with the fountain roll 101, as shown in Fig. 7 of the drawings. As the plunger 86 approaches the plane of feed of the blanks a blank is arrested by fingers 31 to hold it in proper 40 registered position beneath the plunger, so that the paste applying pad 86 will be brought down into contact with the blank and apply paste thereto around the window cut into the blank.

45 Immediately after the application of the paste to the blank around the window opening, the second set of gage fingers releases the blank, in order to permit the conveying tapes 15 and 16 to carry it forward to position beneath the final operating device for applying the transparent patch to the window. This patch applying device will now be explained.

50 Mounted in the standards 8 beneath the plane of feed of sheets is a transverse bar or block 130. A reciprocating cross head 135 is mounted in the vertical guideways or slots of standards 8 above the transverse bar 130. This cross head 135 is formed with a cushioned lower face having a plurality of suction openings 136 communicating with the suction chamber 137. The flexible air pipe or hose 138 leads from suction chamber 137 to the upper end of the exhaust pump 140

which is mounted upon a transverse bar 146 65 supported at its ends in the uprights 142 secured to the standards 8. 143 are links or pitmen trunnioned to the opposite ends of the cross head 135 and extending down and journaled upon the crank pins 144^a carried by crank disk 144 and gear wheel 206, 70 secured to the opposite ends of transverse shaft 51. By these means the cross head 135 is reciprocated vertically in its guideways.

The piston 140^b (indicated by dotted lines 75 in Fig. 3) of the suction pump 140 is connected by the piston rod 145 with the cross head 135, so that the downward movement of cross head 135 exhausts the air from the suction chamber 137 and enables the cross 80 head to take hold of the strip or patch of paper for conveying it to the previously pasted surface of the blank as will presently be explained.

150 is a roll of transparent paper from 85 which the patches are taken. This roll 150 is mounted upon a shaft 151 supported in the upper socketed ends of bracket arms 152 mounted upon the standards 7. The web of paper passes from the roll 150 to a pair of 90 feed rolls 155, 156, which are journaled at suitable supports 157 secured between the standards 8. The shaft of the feed wheel 155 is extended at one end to support a ratchet wheel 160 which is fixed to the shaft, 95 and the gear wheel 161, which is freely journaled upon the shaft. The gear wheel 161 carries a dog or pawl 162 which engages the ratchet wheel 160. A rack bar 165 is pivoted upon crank pin 165^a upon gear 205 100 105 and extends therefrom through a supporting guide bracket 166 by which it is held in mesh with the gear wheel 161. By reason of the reciprocation of the rack bar 165 the feed wheels 155 and 156 are given an intermittent feeding motion for feeding a section of the web from roll 150 into position 110 to be taken by the patch applying plunger or cross head.

115 Adjacent to the feed rolls 155 and 156 is a transverse bar 170 to which is secured a cutter plate 171 over which the end of the web of paper is projected by the feeding rolls. Upon the inner side of the plunger or cross head 135 a knife blade 175 is secured at its upper edge by screws 176, while adjusting screws or bolts 177 are threaded through the bar 135 and engage the blade 175 below its points of attachment with the bar, so as to adjust the cutting edge of the 120 blade with reference to the cutter plate 171. The blade 175 is arranged to coöperate with the cutting plate 171 to sever a piece of the web 150 between them simultaneously with the action of the plunger 135 in taking hold 125 of the separated patch by suction. When the patch is severed and held upon the plunger 135, the plunger continues down-

wardly until the patch is pressed firmly against the pasted surface of the blank to cause the patch to cover the window opening of the blank. Immediately following the 5 application of the patch to the blank, the suction in chamber 137 is broken and the patch released by the upward movement of the plunger. The gage fingers beneath the patch applying device then move out of the 10 way and conveyer tapes 15 and 16 carry the completed blank out of the machine between the delivery tape rollers 12 and 13. The blank can be received by any suitable mechanism such for instance as a receiving 15 table provided with the usual jogging mechanism or the blanks can be passed to the printing press for printing, or to an envelop machine or any mechanism arranged to operate upon them.

20 The various operative parts of the machine above described may be actuated in proper time relation by any suitable mechanism. I have illustrated a driving shaft 200 suitably journaled in the machine frame 25 and provided with a belt pulley 201 and a pinion 202, the latter of which meshes with the large gear 203 secured to the transverse shaft 76 beneath the window cutting device. This gear 203 meshes on one side with the 30 gear 204 keyed to the shaft of the lower feeding in tape roller 11 by which the two rollers and tapes are partially driven. The gear 203 also meshes with a large gear 205 upon shaft 92 beneath the paste applying 35 device, and this gear 205 meshes with and drives a large gear 206, secured to the shaft 51 beneath the patch applying device. Gear 206 meshes with and drives the smaller gear 207 fixed to the shaft of lower delivery tape 40 roller 13 which assists in driving the endless tapes 15 and 16. In the operation of the machine sheets or partially formed blanks are fed in any suitable manner to the feeding in tape rollers 10 and 11 and are carried 45 through the machine by the conveyer formed of the two pairs of tapes 15 and 16. These tapes 15 and 16 engage the lateral wings or portions of the sheets or blanks above and below to convey them through the machine, 50 and at each position beneath the blank operating devices (the window cutting device, the paste applying device and the patch applying device) a sheet or blank is engaged upon each side of its central longitudinal 55 line and arrested while the feed tapes or belts continually move and slide over and under the arrested sheet or blank. After the machine has received three successive sheets or blanks it will be understood that 60 during its operation there will always be three sheets or blanks in successive stages of formation in the machine. The operating mechanism is so arranged that the window cutting device, the paste applying de-

vice and the patch applying device all operate simultaneously so that while the window is being cut in the last blank of the series, the preceding two sheets or blanks are having paste applied and a patch applied upon them, respectively. The sheet or blank 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300

What I claim is:

1. In a machine of the character described, the combination of a continuously operating sheet or blank conveyer, a window cutting device, a paste applying device, a patch applying device and means for simultaneously operating said cutting, pasting and patch applying devices, with a plurality of sheet arresting fingers arranged in the path of sheets and adapted to arrest sheets or blanks in operative relation to said devices without interfering with the continuous motion of the conveyer and means for simultaneously operating said fingers.

2. In a machine of the character described, the combination of the continuously operating endless conveying tapes, a window cutting device, a paste applying device, a patch applying device, means for simultaneously operating said cutting, pasting and patch applying devices, with a plurality of sheet arresting fingers arranged in the path of sheets and adapted to arrest sheets or blanks in operative relation to said devices without interfering with the continuous motion of the tapes, and means for simultaneously operating said fingers.

3. In a machine of the character described, the combination of a sheet or blank conveyer, means for applying paste to said sheets or blanks, and mechanism for applying patches to said blanks, said patch applying mechanism comprising an intermittently operated strip feeding device, a stationary knife mounted adjacent to said feeding device, a patch applying plunger having means for holding a patch and a movable knife mounted upon said plunger and coöperative with said stationary knife for severing a patch from the strip.

4. In a machine of the character described, the combination of a sheet or blank conveyer, means for applying paste to said sheets or blanks, and mechanism for applying patches to said blanks, said patch applying mechanism comprising an intermittently operated strip feeding device, a patch applying plunger having suction openings in its patch engaging face, a suction pump communicating with said suction openings, means supporting said suction pump above said plunger, a piston rod extending from the pump piston

and connected with said plunger, and a strip severing device.

5. In a machine of the character described, the combination with a continuously operating sheet or blank conveyer, a window cutting device, a paste applying device, a patch applying device and means for arresting the sheets or blanks in three successive positions

of dwell in operative relation to the window cutting, paste applying and patch applying devices, respectively, without interfering with the continuous motion of the conveyer.

MATTHEW VIERENGEL.
